UNITED STATES PATENT OFFICE.

EDWARD F. EDGECOMB, OF MINOT, ASSIGNOR OF ONE-HALF TO CHARLES H. MILLIKEN, OF POLAND, MAINE.

PRINTING-PRESS.

SPECIFICATION forming part of Letters Patent No. 437,184, dated September 30, 1890.

Application filed May 13, 1889. Serial No. 310,520. (No model.)

To all whom it may concern:

Be it known that I, EDWARD F. EDGECOMB, residing at Minot, in the county of Androscoggin and State of Maine, have invented certain new and useful Improvements in Printing-Presses; and I do hereby declare that the following is a full, clear, and exact description of the invention, which will enable others skilled in the art to which it appertains to make and use the same.

Figure 1 is a sectional view of my newly-organized printing-press. Figs. 2 and 3 are details, partly in section, showing end and vertical sections, respectively, of the peculiar printing and impression cylinders used in my invention. Figs. 4 and 5 are details, end view and vertical section, respectively, showing the construction of the peculiar mechanism used for registering the adjustment of one cylinder and its mate, or of one pair of cylinders with another pair. Fig. 6 is a detail showing the reel-stand and the mechanism for adjusting and centering a web of paper therein. Figs. 7 and 8 are other details of the reel-stand. Fig. 9 is a side view of the printing-press, wherein is shown the disposition of the gears, whereby the second cylinder of each pair registers with the first pair lying in the same horizontal plane. Fig. 10 is a side view wherein is shown the disposition of the gears whereby the several parts are driven, and also shows the mechanism for registering one set of printing-cylinders with another set of printing-cylinders placed in the same vertical plane.

In the drawings I have shown simply those parts of a printing-press deemed indispensable to illustrate my features of invention, leaving out some parts which are common and well known to those skilled in the art.

In the several figures of the drawings, the same reference-numerals are used to point out corresponding parts.

My invention relates to certain novel and ingenious improvements in continuous web-printing presses. The invention is devoted more especially to the improvement of that class of printing-presses which print upon one or both sides of a web of paper, fabric, or other material going once through the press.

In this class of printing-presses it is absolutely essential that the printing-forms should exactly register.

The nature of my invention and its several features consist in the various constructions, adaptations, and combinations of mechanical parts, to be hereinafter specifically described, and pointed out in the claims.

1 designates the main side frames of the printing-press, adapted to carry all the operative parts.

2 are cylinders provided with shafts or spindles 3, which find proper or suitable bearings in the main frames 1. The cylinders 2 may be either type or impression cylinders. They are arranged in pairs. In the accompanying drawings three pairs are shown. In practice, however, any desired number of pairs may be employed according to the work to be done.

The cylinders 2 are of peculiar construction, and constitute one of the chief elements of my invention in printing-presses. They are made as follows: Disks 4 are affixed to each shaft 3 just inside the sides of the main frames 1. In the periphery of each disk is cut a T-path 5. 6 are bolts, the heads of which lie in the T-paths 5. 7 are plates curved to correspond with the periphery of the disks 4. The plates are provided with perforations to fit the bolts 6, to which they are rigidly connected by means of nuts 8. The outside face of each plate 7 is finished to a true surface—that is, a surface smooth and even. Upon this surface stereotype-plates and the like may be fastened by any well-known method, or the plate may be covered with a material which will constitute a tympan or impressing-plate.

The above method of attaching the plates to the disks has one great advantage, for by loosening the nuts 8 the plates 7 can be separated from each other to any desired distance, can be entirely removed, or can be pushed close together and form a true cylinder, which shall be entirely a type-cylinder or entirely an impressing-cylinder, or a combination of these two—that is to say, a cylinder partly type and partly impressing; or a pair of cylinders may be arranged each with alternate impressing-plates and type-plates, by

which means one pair of cylinders will print first upon one side and then upon the other side of the paper. Thus a web of any material while passing between any pair of cylinders can be printed wholly upon one side or upon both sides or at alternate intervals on opposite sides.

Another element of my invention consists in the novel mechanisms designed for adjusting the cylinders with relation to each other, so that they can be readily put into exact register with each other. On the ends of the spindles 3, outside the main frame, are set gears 9 and 9². In the outer face of each gear is cut a T-path 11, in which is placed the head of a bolt 12. Near the periphery of each of the gears 9 and 9² is placed a scale 13, graduated to fractional spaces to correspond to the circumference of the cylinder. An index or finger 14 is rigidly affixed to the end of the spindle 3 by means of a pin 15. The bolt 12, lying in the T-path 11, projects through the finger, and is provided at its end with a thumb-nut 16 for rigidly clamping the index 14 and gear together at any desired point. In Fig. 9 there is shown parallel with gears 9 a corresponding vertical series of gears 9', and these gears 9 and 9' mesh in pairs, as is also shown in said figure. The gears 9 in vertical line (best shown at the right in Fig. 9) are loosely affixed to the shafts 3. The other gears 9', (shown in vertical line on this side of the machine,) are made integral with their shafts. Still referring to Fig. 9, the indexes 14 are firmly pinned to the shafts 3. Each gear 9 and its accompanying index 14 can be firmly fastened together by means of the thumb-nut 16 and bolt 12. Thus in each instance a gear 9, index 14, and shaft 3 can be made practically rigid, so as to rotate together, as if integrally united. On the other side of the machine the gears 9² (see Fig. 10) are also loosely connected with their shafts, and by means of their accompanying indexes, thumb-nuts, and bolts can be made rigid, too, and caused to rotate with their shafts in the same manner as the gears 9, just as above set out. Power is applied by belt, as usual, to the pulley 17, (see Fig. 10,) which also carries an intermediate gear 19, meshing with and communicating power to the two lower gears 9². The upper of these gears meshes with and rotates an intermediate gear 20, which in turn transmits the power to the top gear 9². By the above it will be seen that each of the cylinder-gears, by which motion is transmitted from the main turning-gear to a pair of cylinders, and each of the gears of a pair of cylinders which turns its mate or second cylinder, is provided with the registering adjustment above described.

In a press which would be capable of printing in two or more different places upon one or both sides of the web the cylinders would be made up of alternate plates—first a stereotype or type plate and then an impressing-plate continuously around each cylinder. The

impressing-plate of one cylinder of each pair should be in exact relation with the proper type-plate of its mate, (in the same horizontal plane,) and if when the plates were placed in position and a web of paper passed through the machine to print it was found they were not in proper adjustment with each other, the machine would be timed as follows: The thumb-nut on the side shown in Fig. 9 would be loosened to allow the index 14 to be freed from contact with the gear, and consequently the gear 9' on the same horizontal line and meshing with gear 9 could then be moved in such a direction and at such a distance as the sheet or printing was shown to be out of register by simply rotating the loose gear 9, which, in its movement, carries the gear 9'. This operation is easily accomplished by the hand, or the same results can be accomplished by swinging the index 14, which is pinned to the shaft 3, and turning the shaft and accompanying cylinder into register with the corresponding cylinder in the pair. The thumb-nut 16 would then be fastened. A similar operation would be performed with each of the three pairs of cylinders, and when completed each cylinder of a pair would be adjusted in proper relation with its mate. If, after this was done, it was found that the printing by the second pair of cylinders did not register with that done by the first pair, then the adjustment upon the other side of the machine, (see Fig. 10,) whereby the cylinders are adjusted in the vertical plane, would be utilized until the work was brought into perfect register. By these two adjustments in a vertical and horizontal plane I am enabled to use any number of cylinders and print any number of impressions.

For inking the cylinders any of the well-known systems of inking-rollers may be used. I have not considered it requisite to display inking-rollers and details of mechanisms for working them, for the nature of my improvements has no relation to them.

Referring to the drawings, Figs. 6, 7, and 8 show the details of construction of the web-reel to be used in connection with my printing-press. The rolls of paper for perfecting-presses are usually wound upon iron cores, which vary in internal diameter. In the usual method of mounting these rolls in the reel-stand it is customary to use a shaft smaller than the hole in the roll-core, upon which are two cones fastened by set-screws. In practice considerable time will be lost in adjusting the cones upon the roll-shaft, so as to bring the roll of paper into its proper place upon the shaft to feed directly into the press. To obviate this difficulty, the following construction is resorted to: The reel-shaft 21 and cones 22 are made the same as in other reels. The ends of the reel-shaft 21 are journaled in suitable boxes 23 and 24 in the stand or frame 25. One of the journals of the reel-shaft is a plain bearing, so as to allow the shaft to move freely longitudinally through

its bearing. The other journal is provided with an enlargement or collar 28, which prevents the journal from having any longitudinal movement other than a movement which 5 may be given to the box 24 in which it works. This box is capable of being moved horizontally in the frame. An arm 29, fixed to the box 24, extends outwardly and turns to a right angle. At its outer end the arm is 10 pierced by a thumb-screw 30, which is threaded into the frame 25. By turning the thumb-screw 30 in or out the box 24 can be moved longitudinally in its seat, and with it the shaft 21 and roll of paper carried thereon. This 15 adjustment enables the operator to bring the roll of paper into any desired position without loss of time and inconvenience.

In Fig. 9, 31 designates the feed-roll, which is arranged at the top of the press and carries 20 at one end a gear 32, which meshes with an intermediate gear 33. This intermediate gear engages the gear 9 upon the cylinder 2 just under it, and when the cylinder is in revolution transmits motion to the feed-roll. 25 Ridging-rolls for giving proper tension to the feed are designated by 34 35.

36 shows in edge view the position of a series of endless bands or tapes for carrying the web along through the press after it has 30 passed the printing-cylinders. These tapes pass over tape-rolls 37, 38, 39, and 40. The forward travel of the tapes, which is constant when the press is at work, is accomplished by power transmitted from the lower left-hand 35 cylinder-gear 9 to the gears 41 and 42 through the intermediate gear 43.

44 and 45, Fig. 1, are rolls carrying suitable means for slitting the web into any desired width or widths after it is printed. The roll 40 44 carries a gear 46, Fig. 10. Rotation is imparted to the slitting-roll 44 by power transmitted through the medium of the intermediate gear 47, which is in mesh with the lower cylinder-gear 9².

45 The gear 46, driving the slitting-roll, connects with an intermediate gear 48, which in turn meshes with a gear 49, which imparts revolution to rolls 50 and 51, provided with proper adjuncts for transversely perforating 50 or creasing the printed web or strips.

I do not intend to use for the slitting or perforating any mechanisms new to the art. Therefore I have simply shown the position in the machine of the rolls devoted to those 55 purposes without entering into any minute description of their construction.

The rolls 52 53 are tension-rolls driven by any convenient means. They are held against each other with a light friction, and their speed 60 is slightly faster than the speed of the other rolls, to keep the web drawn tight in its passage through the press while the several operations of printing are being performed.

The operation of the press is as follows: A 65 roll of paper is placed on the reel-shaft 21 and properly centered. The end of the web is carried over the feed-roll 31 and is passed

between the first pair of cylinders 2 and receives its first impression of printing. It is then carried vertically downward in the press 70 between the successive pairs of plate-cylinders and impressing-cylinders until it reaches the tape-rolls 37 38. It passes between them and rests upon the tapes 36. The direction of the paper is now changed to conform to the 75 position of the tapes, by which it is carried along first to the slitting-rolls 44 45, and then to the perforating or creasing rolls 50 51. The paper is then passed between the tension-rolls 52 53 and out of the press. 80

The press herein represented has been explained thus far as especially designed for ordinary letter-press printing with type or stereotyped plates upon paper from an endless web. I do not limit myself to that style 85 of printing, for, by a proper substitution of plates upon the several plate-cylinders and pairs of cylinders, and a proper change of ink in the inking-fountains, the press can be immediately transformed into a perfecting color- 90 printing press, which will print in one or a plurality of colors or tints upon one or both sides of the web; or it may be used as a combination-press capable of printing in colors at one point and in letter-press at another 95 point. This great adaptability of the press to radically different kinds of printing and combinations of the same I am able to bring about by the peculiar construction of the printing and impressing cylinders hereinbefore shown and explained. 100

What I claim as my invention, and desire to secure to myself by Letters Patent, is—

1. In a printing-press, the herein-described type or impressing cylinders, composed of the 105 type or tympan carrying plates 7, in combination with the disks 4, each having a peripheral slot cut into a T-path, and bolts 6, confined in said paths and projecting outwardly and provided with nuts, whereby the plates 110 7 and disks 4 can be fastened together at any desired point on the carrying-shaft, substantially as specified.

2. The combination of the cylinders, with the cylinder-shaft 3 and index 14 rigidly 115 pinned thereon, a loose gear provided near its periphery with a graduated scale and a T-path, and mechanisms adapted to fasten the index and gear rigidly together, substantially as and for the purposes described, whereby 120 the cylinders can be adjusted and put into exact register with each other.

3. In a printing-press, the combination, with the reel-stand 25, of the shaft 21, journaled at 23 and 24 in the side bars of said stand, which shaft can move longitudinally in its bearing-box at 23, but is prevented from moving so in its bearing-box at 24 on account of the collars 28 28' on each side of said bearing-box, the arm 29, depending from the stand 25, and the screw 30, passing through a threaded opening in said arm and bearing upon the bearing-box, so that said box can be moved in its seat by said screw and the position of

the shaft thereby adjusted, substantially as specified.

4. The combination of the cylinder-shafts having, respectively, on one side of the machine the vertical gears 9, adapted to be rigidly adjusted, and the vertical and fixed gears 9', parallel to and meshing with the former gears, and the gears 9² at the opposite side of the machine, and the intermediate gears 19 and 20, whereby the horizontal and vertical adjustment of the cylinders can be perfected.

5. In a printing-press, the herein-described cylinder, composed of a series of curved plates, the outside face of each finished to a true surface and all secured in place, substantially in the manner and for the purposes set forth, whereby stereotype-plates may be fast-

ened on the surface or the surface may be covered with a suitable impressing-plate.

6. In a printing-press, the combination, 20 with a pair of type and impression cylinders, of the gears upon the shafts of said cylinders, one of the gears 9' being fast upon its shaft, the other gear 9 being loose upon its shaft and provided with mechanism whereby 25 a pair of cylinders can be brought into exact registry, substantially as set forth.

In testimony that I claim the foregoing as my own I have affixed my signature in the presence of two witnesses.

EDWARD F. EDGEcomb.

Witnesses:
